PC**CLAIM**

The ornamental design for a servo amplifier, as shown and described.

DESCRIPTION

FIG. 1. is a front perspective view of the front, left, and top sides of a servo amplifier showing our new design;

FIG. 2. is a rear perspective view of the rear, right, and bottom sides thereof;

FIG. 3. is a front view thereof;

FIG. 4. is a rear view thereof;

FIG. 5. is a top plan view thereof;

FIG. 6. is a bottom plan view thereof;

FIG. 7. is a right side view thereof; and,

FIG. 8. is a left side view thereof.

The broken lines shown represent portions of the servo amplifier and form no part of the claimed design.
